UNITED STATES PATENT OFFICE.

REUBEN HALEY, OF BEAVER, PENNSYLVANIA, ASSIGNOR TO UNITED STATES GLASS COMPANY, OF PITTSBURGH, PENNSYLVANIA, A CORPORATION OF PENNSYLVANIA.

DESIGN FOR A SYRUP-PITCHER.

43,819.

Specification for Design.

Patented Apr. 8, 1913.

Application filed November 22, 1912. Serial No. 733,006. Term of patent 7 years.

To all whom it may concern:

Be it known that I, REUBEN HALEY, a citizen of the United States, and residing at Beaver, in the county of Beaver and State of Pennsylvania, have invented a certain new, original, and ornamental Design for a Syrup-Pitcher, shown in the accompanying drawing, which is a view in perspective of the same.

The pitcher body is provided at one side with the ornamental loop handle, and at the opposite side the upper portion of the body is bulged with the top edge of the bulge curved downwardly and outwardly in graceful lines to form the ornamental spout. The external surface of the body, immediately beneath the top edge, is formed with a surrounding band of ribbon or panel form, the portion thereof extending around the

spout having the bulge and downwardly curved formation of the spout edge, and formed on this surrounding band or panel is the superficial ornamentation of walls of Troy design, as shown. The pitcher top is symmetrical with the shape of the upper portion of the pitcher body, including the extension of the top which is symmetrical with the spout. Projecting upwardly from the top and disposed rearwardly is the ornamental handle, as shown.

I claim:—

The ornamental design for a syrup pitcher, as shown.

REUBEN HALEY.
